CLAIM

I claim the ornamental design for accessories for inflation and repair of tires, as shown.

DESCRIPTION

FIG. 1 is a top/side perspective of view of our first embodiment of said new design for accessories for inflation and repair of tires;

FIG. 2 is a rear elevation view thereof;

FIG. 3 is a front elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an exploded top/side perspective view for accessories for inflation and repair of tires showing a second embodiment of my new design;

FIG. 9 is a front elevation view of FIG. 8;

FIG. 10 is a rear elevation view of FIG. 8;

FIG. 11 is a left side elevation view of FIG. 8;

FIG. 12 is a right side elevation view of FIG. 8;

FIG. 13 is a top plan view of FIG. 8; and,

FIG. 14 is a bottom plan view of FIG. 8.

The broken lines are for illustrative purposes only and form no part of the claimed design.
